UNITED STATES PATENT OFFICE.

JOHN M. MILLER, OF SEWICKLEY, PENNSYLVANIA, ASSIGNOR TO HEPBURN WALKER,
OF SEWICKLEY, PENNSYLVANIA.

LIQUID STORAGE AND DELIVERY APPARATUS.

1,307,827.

Specification of Letters Patent. Patented June 24, 1919.

Application filed January 9, 1918. Serial No. 211,037.

To all whom it may concern:

Be it known that I, JOHN M. MILLER, residing at Sewickley, in the county of Allegheny and State of Pennsylvania, a citizen 5 of the United States, have invented or discovered certain new and useful Improvements in Liquid Storage and Delivery Apparatus, of which improvements the following is a specification.

10 My invention relates to apparatus for liquid storage and delivery systems of the general type wherein a liquid is stored in a reservoir and before being sold is caused to flow into a measuring tank from which all, 15 or any desired portion, may be withdrawn, the measuring tank being so constructed that the purchaser may see the amount of liquid sold to him.

20 While my invention is not limited to apparatus for vending any specific kind of liquid, it is particularly applicable to the vending of gasoline, and in the following description will be explained in its adaptability to such use.

25 The vending of gasoline by means of such apparatus is usually done at garages or service stations by employees. While the measuring tank, constructed as explained, protects the purchaser against short or fraudulent 30 measure of the gasoline, in the forms of apparatus used heretofore no adequate means is provided to protect the proprietor against an employee making sales of gasoline and withholding the purchase money.

35 The object of my invention is primarily to provide, for a liquid storage and delivery system, apparatus which will prevent the defrauding of a proprietor by an employee. A further object is to provide apparatus of 40 the character described which will be simple in construction, and which may be easily and quickly operated.

In vending apparatus and systems of the character contemplated herein, the gasoline 45 is usually caused to flow from the storage reservoir to the measuring tank either by means of air pressure applied to the gasoline in the storage reservoir, or by means of a vacuum formed in the measuring tank or 50 in a conduit leading thereto. In the accompanying sheets of drawings I have shown two embodiments of my invention, one adapted particularly for the pressure discharge of the gasoline from the storage reservoir,

and the other for the vacuum lift of the 55 gasoline into the measuring tank.

In the drawings, Figure 1 is a diagrammatic representation of the various tanks, reservoirs and connecting pipes in the pressure system; Fig. 2 a diagrammatic representation of a compound valve used for controlling the flow of air and gasoline in the system of Fig. 1. Fig. 3 is a side view 60 of a portion of the apparatus, part of the casing being indicated in vertical central 65 section to show the mechanism therein; Fig. 4 a vertical sectional view to enlarged scale taken on the line IV—IV Fig. 3; Fig. 5 a vertical sectional view taken on the line 70 V—V Fig. 4; Fig. 6 an enlarged scale view 75 of the central portion of Fig. 3; Fig. 7 a combined face and sectional view of part of the registering mechanism shown in Figs. 3, 4 and 6, the plane of view being indicated by the broken line VII—VII, Fig. 8; Fig. 8 80 a plan view of the mechanism of Fig. 7; Fig. 9 a view of a detail of construction referred to hereinafter; Fig. 10 a sectional view taken on the line X—X, Fig. 9; Fig. 11 a view similar to Fig. 1, showing a vacuum system apparatus; and Fig. 12 a diagrammatic representation of a compound 85 valve used in the apparatus of Fig. 11.

Referring first to the apparatus for the pressure system, as diagrammatically represented in Fig. 1, the main body of gasoline may be stored in a reservoir 1, usually placed under ground for safety, and below this reservoir there may be placed a smaller storage reservoir 2 communicating with the 90 main reservoir 1 by means of a conduit 3 in which there is placed a suitable check valve 4 permitting flow of the gasoline from the larger to the smaller reservoir, but preventing the flow of either air or gasoline in the 95 opposite direction. Connected to the reservoir 2 by means of a conduit 5 there is a measuring tank 6 made of suitably protected glass, calibrated and graduated to indicate 100 units of liquid measure, such as gallons and fractions thereof, or otherwise constructed to render visible the contents thereof. The conduit 5 is discontinuous, the main portion extending to a controlling valve 7, and a second portion 5^a extending from such 105 valve to a position a short distance above the bottom of the tank 6.

Within the tank 6 there is a second con-

duit 8 having its open end above the upper end of the conduit 5^a, the two ends of these conduits being preferably so spaced vertically that the volume of liquid that may be placed in the tank between the horizontal planes of the ends of the pipes will be five gallons or some other unit of measurement.

The conduit 8 leads to the valve 7 and from thence by an extension 8^a to a return tank 9, the construction of which will be presently explained. The bottom of the tank 9 is connected to a conduit 10 through which gasoline may be returned to the storage reservoir. Preferably this conduit connects the tank 9 with the filling conduit 5. By such construction the quantity of gasoline in excess of the required five gallons, caused to flow into the tank 6 from the reservoir 2, may be returned to this reservoir through the conduits 8 and 8^a, tank 9, and conduits 10 and 5.

To deliver gasoline from the tank 6 to a customer, a suitable delivery conduit 11 extends from the valve 7. By the turning of such valve the conduit 11 is adapted to be placed in communication with the conduit 5^a, so that any desired quantity of gasoline, not exceeding in this instance five gallons, may be withdrawn from the measuring tank.

As already stated, air pressure is, in this system, utilized to cause the gasoline to flow from the reservoir 2 to the measuring tank 6. One feature of my invention consists of utilizing a single source of air pressure for causing the gasoline to flow both from the reservoir 2 to the measuring tank 6 and from such tank through the discharge conduit. Thus such tank may be more quickly emptied than if the gasoline were permitted to flow therefrom only under the action of gravity.

Preferably the control of flow of gasoline and air is effected by a single controlling element, and, in the specific embodiment of my invention, I have shown a compound valve for this purpose. It will, however, be understood that, in its broader aspects, my invention is not limited to the use of a compound valve. The detailed construction of the valve is explained herein-after. For the present it is sufficient to state that, for controlling the air conduits, the valve casing 12 is provided with suitable ports which are in communication with various conduits, namely, an air conduit 13 leading from a source of pressure supply, an air conduit 14 extending within the conduit 8 to a point adjacent to the top of the tank 6, a vent conduit 15 leading to the main storage reservoir 1, and a pressure conduit 16 leading to the auxiliary storage reservoir 2. Thus, air pressure from the conduit 13 may be caused to flow first through the conduit 16 to cause gasoline to flow from the reservoir 2 through conduits 5 and 5^a into the tank 6, and thereafter may be caused

to flow through the conduit 14 into the tank 6 to forcibly eject the gasoline previously delivered thereto. While the gasoline is being caused to flow into the tank 6 the air and vapors in such tank are carried by conduits 14 and 15 to the main storage reservoir 1.

Ordinarily more than five gallons will be caused to flow into the tank 6 each time it is filled. The volume of gasoline in excess of five gallons flows through the conduits 8 and 8^a into the return tank 9, the valve 7 being, as hereinafter explained, turned to permit such flow.

To the end that the amount of gasoline sold may be properly metered, and a record thereof kept, and to the further end that gasoline may not be delivered in excess of the amount metered and registered, the measuring tank is constructed to be filled each time with a constant unit volume of gasoline, and a registering device is coördinated with the movement of the valve 7 so that each time that the valve is turned to fill the measuring tank the registering device is advanced to indicate such unit volume. The unit volume, for which the apparatus shown herein is constructed, is five gallons, and in the subsequent description the apparatus will be explained as being so constructed. The usual purchaser of gasoline for automobiles, and the like, obtains it in multiples of five gallons. However, this is not always the case, and accordingly means, coördinated with the operation of the valve 7, are provided for measuring the volume of gasoline remaining in the tank 6, and for recording such volume. While the volume of gasoline thus remaining in tank 6 may be variously recorded, I preferably provide means for turning backwardly the aforementioned registering device in proportion to the volume of gasoline remaining in tank 6 and returned to the storage reservoir.

In the further description of this form of my invention, I will explain, first, the construction of the registering device specifically shown herein, together with the mechanism for measuring the volume of gasoline remaining in the tank 6 after a customer has been supplied; and, secondly, the detail construction and operation of the valve 7.

As already stated, the gasoline taken into the tank 6 in excess of five gallons flows through conduits 8 and 8^a to the return measuring tank 9. However this excess volume of gasoline flows immediately from the tank 9 in a manner presently to be explained, and is not measured in such tank. The gasoline remaining in the tank 6 after a sale of less than five gallons is, by the rotation of the valve 7, also caused to flow through the conduits 5^a and 8^a to the tank 9 and is measured therein. The con-

struction of the return measuring tank 9 is particularly illustrated in Figs. 3 and 5. Within the tank there is a float 17 secured at its upper and lower sides to a suitable chain 18 which extends around upper and lower sprockets 19 and 20, respectively. Near the bottom of the tank 9 there is attached a suitable valve casing 21 which communicates with the tank 9 by a port 22. A 5 spring-pressed valve 23, attached to a rod 24 which is inclosed in a suitable pipe 25, controls communication between the lower end of the tank 9 and the conduit 10. The pipe 25 extends above the highest permissible 10 level of gasolene in tank 9 for the purpose of making it unnecessary to pack the valve rod 24. By mechanism presently to be described, the valve rod 24 is caused to rise by the rotation of the valve 7 so that the 15 gasoline taken into the tank 6 in excess of five gallons may flow into the tank 9, and from thence directly through the conduits 10 and 5 to the storage reservoir 2 without raising the float 17. When the valve 7 is turned to cause the gasolene remaining in 20 the tank 6 after a sale thereof to flow into the tank 9, the valve 23 is closed so that the float 17 is caused to rise in proportion to the volume of the gasolene in the tank 9. 25

With respect to the detailed construction of the bottom of the tank 9, the port 22 is placed at such elevation that the float 17 will be held in equilibrium by a body of gasolene below such port, such body of gasolene 30 remaining in the bottom of the tank 9 after the above explained overflow operation. Thus, after the valve 23 has been closed, but a small quantity of gasolene is required to cause the float 9 to rise to a higher level. 35

The valve 7, which may be turned by suitable handle or crank 26, is so constructed that it turns through one complete revolution to effect a single cycle of operation of the vending apparatus. To this valve there 40 is attached a cam 27 adapted to move a lever 28 secured to the upper end of the valve rod 24. The cam is so constructed that the valve 23 is held closed during the filling of the tank 6, open during the overflow operation, closed during the return measuring operation, and open subsequently to the last mentioned operation and until the valve 7 is again turned to fill the tank 6. The last mentioned position is indicated in Fig. 6. As 45 there indicated a plurality of meter disks 29 are secured to shafts 30 carried by an arm 31, pivoted to the tank 9, as at 32, and held yieldingly in the position indicated in Fig. 6 by a spring 33. To each shaft 30 there is attached a pinion 99, a locking disk 100 provided with a laterally projecting pin 101, and a hub 102 provided with a recess 103 adjacent to the pin 101. The cylindrical portion of each hub 102 fits into one of a 50 series of recesses formed on the periphery of the locking disks 100. By such construction each left-hand shaft 30 is, by the hub 102 on the adjacent right-hand shaft 30, held against rotation until such right-hand shaft has made one complete revolution. 55 One complete revolution of the right hand disk 29, as viewed in Figs. 7 and 8, registers ten gallons, a complete revolution of the adjacent disk registers one hundred gallons, and so on in multiples of tens. The manner of turning the right hand disk 29, both forwardly and backwardly will be presently explained. When, at the end of a complete revolution of the right hand disk 29, the pin 101 on the right-hand locking disk 100 60 engages a tooth on the pinion 99 of the adjacent shaft 30, the recess 103 of the right hand hub 102 will be in a position to permit such adjacent shaft 30 to be turned one tenth of a revolution. The rotation of the 65 other disks is effected in the same manner.

For advancing the registering device five gallons upon the rotation of the valve 7, such valve is provided with a sprocket wheel 34, which, through a suitable sprocket chain and system of gears, as clearly shown in Fig. 6, drives a spur gear 35 provided with a laterally projecting pin 101^a. This pin drives the right hand disk 29 in the manner just explained. For raising the arm 31 so that the pin 101^a will engage the right hand gear 99 carried by such arm, the valve rod 24 is provided with a shoulder 36 adapted to engage and lift the outer end of the arm when the valve is open. The gear ratio between the sprocket 34 and spur gear 35, and the length of the largest radius arc 104 of the cam 27 are such that the registering device will be advanced five gallons during such portion of the rotation of the valve 7 as is required to maintain open the valve 23. 70

Because the measuring tank 6 is each time filled with five gallons, it is unnecessary to register fractions of a gallon except when the return volume of gasolene is being metered and registered. Accordingly a fraction-registering disk 29^a, Fig. 9, is preferably attached to a shaft 38, which through sprocket 19 attached to it, is rotated by the float mechanism. Preferably the reverse 75 movement or backward turning of the register is effected by the downward movement of the float. To such end the shaft 38 has keyed thereto a ratchet 39, and has rotatably mounted upon it a sleeve 40 to the outer end of which the disk 29^a is attached. The inner end of the sleeve 40 is provided with a ratchet having secured to one of its sides a pawl 42 adapted to engage the teeth of the ratchet 39, and to the other side a pin 101^b 80 adapted to turn the right hand gear 99 of the arm 31. A pawl 43 is provided for the engagement of the ratchet 41. In operation, as the float rises, the turning of the shaft 38 is ineffective to turn the disk 29^a, because of 85

- the engagement of the ratchet 41 by the pawl 43. However, when the float descends, the ratchet 39 engages the pawl 42, and, through ratchet 41 and sleeve 40, turns the disk 29. 5 It will be understood that a complete rotation of the shaft 38, and in consequence thereof of the ratchet 41, causes the right hand disk 29 of arm 31 to turn one tenth of a revolution.
- 10 Turning now to the construction of the valve 7 as illustrated diagrammatically in Fig. 2, the portion of the valve to the left of the dotted line 44 controls the flow of compressed air and that to the right thereof 15 the flow of gasoline. During one complete rotation of the valve there are five stopping points for controlling the flow of gasoline and compressed air, as well as for controlling vent lines and the position of the valve 20 23. In the subsequent description of the valve, these five positions will be designated as zero position, and Nos. 1, 2, 3 and 4 positions.
- 25 The flow of gasoline and compressed air, 25 the vent lines, and the position of the valve 23 are, for the several positions of the valve, as follows:
- 30 Zero position:—gasoline from tank 6 to tank 9; vent from tank 6 to reservoir 1; valve 23 open.
- 35 No. 1 position:—gasoline from reservoir 1 to tank 6; air from source 13 to reservoir 2; vent from tank 6 to reservoir 1; valve 23 closed.
- 40 No. 2 position:—gasoline overflow from tank 6 to tank 9; air from source 13 to tank 6; valve 23 open.
- 45 No. 3 position:—gasoline from tank 6 to delivery conduit 11; air from source 13 to tank 6; reservoir 2 vented to reservoir 1; valve 23 closed.
- 50 No. 4 position:—gasoline from tank 6 to tank 9; tank 6 vented to reservoir 1; valve 23 closed.
- 55 With the foregoing synopsis of the operation of the valve, its detailed construction may be readily understood from the diagrammatic representation thereof. It will be understood, however, that in actual practice the ports are necessarily somewhat differently constructed than indicated in Fig. 2, the construction shown in this figure being primarily for the purpose of facilitating an understanding of the operation of the valve.
- 60 Considering first the gasoline-controlling portion of the valve, the casing thereof is provided with two extended ports 45 and 46 communicating with the conduit 5^a leading from the measuring tank; with a port 47 65 communicating with conduit 8 for conducting overflow gasoline from the measuring tank; with ports 48, 49 and 50 communicating with the conduit 8^a leading to the return tank; with a port 51 communicating with the discharge conduit 11; and with a port

52 communicating with the conduit 5 extending from the auxiliary storage reservoir 2. The valve member 7 is provided with a continuous port having transversely disposed legs 53 and 54 connected to each other by a longitudinally disposed portion 55, the leg 53 being adapted in the rotation of the valve to communicate successively with the valve casing ports 52, 49, 46 and 50, and the leg 54 with the valve casing ports 45, 47, 51, and 48. The valve port 53, 54, 55 is, for convenience of illustration, indicated in No. 1 position of the valve, affording communication between the ports 45 and 52 for permitting gasoline to flow from reservoir 2 to tank 6. In No. 2 position the valve port affords communication between the casing ports 47 and 49 for permitting overflow through the pipe 8 to the return tank 9; in No. 3 position between the casing ports 46 and 51 for discharging gasoline from the tank 8 through the discharge conduit 11; in No. 4 position between the casing ports 46 and 48 for returning the unsold gasoline to the return tank 9; and in zero position between the ports 50 and 45 for further permitting the flow from the measuring tank 6 to the return tank 9.

For controlling the flow of compressed air and the venting of the tanks and reservoirs, the valve casing 12 is provided with a port 56 communicating with the vent line 15 leading to the reservoir 1; with a port 57 communicating through conduit 16 with the auxiliary storage reservoir 2; with a port 58 communicating through conduit 14 with the measuring tank 6; and with a port 59 communicating through conduit 13 with the source of air pressure supply. The rotatable valve 7 is provided with longitudinally disposed ports 60 and 61, adapted to afford communication between the several valve casing ports in the manner clearly indicated in the drawing.

From the foregoing synopsis of the five positions of the valve 7, and from the detailed explanation of the gasoline controlling portion of the valve, the operation of the air-controlling portion will be readily understood.

Referring now to the form of apparatus illustrated in Figs. 11 and 12, wherein, as already explained, the gasoline is drawn into the measuring tank by means of a vacuum formed therein, the apparatus, as far as concerns the construction of the measuring tank, the return tank, the indicator device, and the float mechanism, may be the same as that already explained. In this embodiment of my invention, a single storage reservoir 63 is connected, by means of a conduit 64, to a valve 65, which in turn is connected to a measuring tank 66 by a filling conduit 64^a. An overflow pipe 67 extends from the upper portion of the measuring tank 66 to the return tank 9.

tank 66 to the valve 65 and from such valve a conduit 68 extends to a return tank 69. The valve 65 is also connected to a delivery conduit 70. Furthermore, a conduit 71, controlled by a valve 72 (corresponding to the valve 23 of Figs. 1 and 5), extends from the return tank 69 to the filling conduit 64.

For generating a vacuum in the measuring tank 66 there is preferably provided an 10 air pump 73, adapted to be driven by an electric motor 95 the suction side of which pump is connected to the valve 65 by a conduit 74, and the discharge side to such valve by a conduit 75. Leading from this valve 15 there is also a conduit 76 extending to the upper portion of the measuring tank 66, and a conduit 77 extending to the return measuring tank 69.

At one end of the rotatable valve 65 a 20 suitable make-and-break device 79 is provided for controlling the electric current supply through the motor 95 for operating the air-pump 73. Also, as in the first described form of my invention, the valve 72 25 is, through a rod 80, controlled by the rotation of the valve 65.

By connecting both the suction and discharge sides of the air-pump 73 with the valve 65, the vapors formed in the measuring tank 66, while such tank is being filled, 30 may be conducted to the return tank 69 wherein they may be condensed and returned to the storage reservoir 63. Also, the air pump may be used for compressing air 35 which may be led to the measuring tank 66 to facilitate the discharge of gasoline therefrom.

The valve 65 and its casing 81 are diagrammatically represented in Fig. 12 in a 40 manner similar to the valve of Fig. 2. The portion of the valve to the left of the dot-and-dash line 82 controls the flow through the air pressure and suction conduits, while that to the right thereof controls the flow 45 of gasoline. In one complete turning of the valve there are five stopping points for controlling flow through the gasoline and air conduits, and for operating the circuit make-and-break mechanism 79 and the valve 72. 50 The lines of flow communication through the several conduits, the operation of the motor 95, and the position of the valve 72 are, for the several positions of the valve 65 as follows:

55 Zero position:—gasoline from tank 66 to tank 69; air pressure conduits to tank 66; motor idle; valve 72 open.

No. 1 position:—gasoline from reservoir 63 to tank 66; suction from tank 66; pressure to tank 69; motor running; valve 72 closed.

No. 2 position:—gasoline overflow from tank 66 to tank 69; air pressure to tank 66; suction from tank 69; motor running; valve 72 open.

No. 3 position:—gasoline from tank 66 to delivery conduit 70; air pressure to tank 66; suction from tank 69; motor running; valve 72 closed.

No. 4 position:—gasoline from tank 66 to 70 tank 69; air pressure to tank 66; suction from tank 69; motor running; valve 72 closed.

The several ports in the valve 65 and casing 81 to the right of the line 82, which 75 ports control the flow of gasoline, are the same as the corresponding part of the valve shown in Fig. 2, and hence require no further explanation.

For controlling flow through the suction 80 and air conduits the valve casing 81 is provided with an annular port 83, communicating with the conduit 76 leading to the measuring tank 66; with a port 84 communicating with the conduit 75 from the discharge 85 side of the air pump; with a port 85 communicating with the conduit 74 leading from the suction side of the air pump; and with a port 86 communicating with the conduit 77 leading to the return tank 69. The valve 90 65 is provided with longitudinally disposed ports 87 affording communication between the valve port 83 and ports 84 and 85; and with the ports 88, 89, 90 and 91 affording communication between the valve casing 95 port 86 and ports 84 and 85. From the detailed description of the valve of Fig. 2, and from the foregoing synopsis of the valve of Fig. 12, the operation of this portion of the latter valve may be readily understood 100 without a detailed explanation thereof, it being understood that the relative positions of the ports shown in the drawing is for No. 1 position of the valve.

Detailed descriptions of the operation of 105 the several elements of the apparatus which I have provided have been made in connection with the description of the construction of such elements. It remains only to describe the general operation of the apparatus and system in its attainment of the 110 object of my invention.

In both forms of the apparatus disclosed herein, the turning of the valve-operating element to cause gasoline to flow from the 115 storage reservoir to the measuring tank advances the indicator mechanism, the desired unit volume, in this instance five gallons. In the next step of the operation the volume of gasoline taken into the measuring tank 120 in excess of five gallons flows into the return tank, the valve controlling the flow from the return tank being open so that the excess volume of gasoline is not measured by the float mechanism. The gasoline in the measuring tanks being at the level of the top of the overflow conduit, the valve is turned to No. 3 position wherein any desired quantity of gasoline up to five gallons may be discharged through the delivery conduit, the 125 130

volume thus discharged being gaged by the graduations on the measuring tank. In case the full five gallons is sold to a customer, it is unnecessary to stop the controlling valve 5 at its No. 4 position. However if but a portion of the gasoline is sold, the next step in the operation is to turn the valve to permit the remaining volume of gasoline to flow into the return measuring tank. The valve 10 23 or 72 being closed, the gasoline is retained in the measuring tank, and as it flows therein causes the float to rise. In the final step of the operation the valve controlling the discharge of gasoline from the return 15 measuring tanks is opened, and the gasoline permitted to flow to the storage reservoir. As the gasoline thus flows from the return measuring tank, the float descends and causes the indicator mechanism to be turned back- 20 wardly in proportion to the volume of gasoline in the measuring tank when the valve 23 or 72 is opened.

The characteristic feature of my invention is that, in the practice thereof, an employee 25 may not withdraw gasoline from the storage reservoir and deliver it without having the volume thereof adequately metered.

According to the provision of the patent statute, I have described the principle and 30 operation of my invention, together with the constructions which I now consider to represent the best embodiments thereof. However, I desire to have it understood that, within the scope of the appended claims, my 35 invention may be practised with other forms of construction than those specifically shown and described.

I claim as my invention:

1. In a liquid storage and delivery apparatus, the combination of a storage reservoir, a measuring tank, a filling conduit connecting said reservoir with said tank, a delivery conduit leading from said tank, a return conduit leading from said tank to said 40 reservoir, means for controlling the flow of liquid from the reservoir to the tank and from the tank successively through the delivery and return conduits, and means for measuring the volume of liquid that flows through the return conduit.

2. In a liquid storage and delivery apparatus, the combination of a storage reservoir, a measuring tank, a filling conduit connecting said reservoir and tank, a delivery conduit leading from said tank, a return conduit leading from said tank to said reservoir, means for filling said tank with a unit volume of liquid at each filling operation and for registering said volume, means for 50 controlling the flow of liquid from the tank successively through said delivery and return conduits, and means for measuring the volume of liquid that flows through the return conduit.

3. In a liquid storage and delivery appa-

ratus, the combination of a storage reservoir, a measuring tank, a filling conduit connecting said reservoir and tank, a delivery conduit leading from said tank, a return conduit leading from said tank to said reservoir, means for controlling the flow of liquid from said reservoir to said tank whereby said tank may be filled with a unit volume of liquid at each filling operation, means coöordinated with said controlling 70 means for registering said unit volume, means for controlling the flow of liquid from the tank successively through said delivery and return conduits, and means coöordinated with said last-named controlling means for measuring and registering the volume of liquid that flows through the return conduit. 75

4. In a liquid storage and delivery apparatus, the combination of a storage reservoir, a measuring tank, coöordinated means for filling said tank with a volume of liquid taken from said reservoir and for registering said volume, a discharge conduit leading from said tank, and coöordinated means for returning to the reservoir liquid in the tank and for measuring and registering the volume of liquid so returned. 80

5. In a liquid storage and delivery apparatus, the combination of a storage reservoir, a measuring tank, a conduit between said reservoir and tank, a valve for controlling flow through said conduit, means for filling said tank with a unit volume of fluid taken from said reservoir, a registering device coöordinated with said valve to register 90 said unit volume, a delivery conduit leading from said tank, a return conduit leading from said tank to said reservoir, and means for measuring and registering the volume of liquid that flows through said return conduit 100 after a measured volume of liquid has been withdrawn from said tank through the delivery conduit.

6. In a liquid storage and delivery apparatus, the combination of a storage reservoir, a measuring tank, coöordinated means for filling said tank with a volume of liquid taken from said reservoir and for registering said volume, a delivery conduit leading from said tank, and coöordinated means for returning to the reservoir liquid in the tank and for measuring and deducting from said 110 previously registered volume the volume of liquid so returned to the reservoir. 115

7. In a liquid storage and delivery apparatus, the combination of a storage reservoir, a measuring tank, coöordinated means for filling said tank with a unit volume of liquid taken from said reservoir and for registering said unit volume, means for returning unmeasured to said reservoir the liquid taken therein in excess of said unit volume, a delivery conduit leading from said tank, and coöordinated means for returning to said reservoir the liquid undelivered from 120 125 130

said tank and for measuring and registering the volume of the last-mentioned returned liquid.

8. In a liquid storage and delivery apparatus, the combination of a storage reservoir, a measuring tank, a filling conduit connecting said reservoir with said tank, a delivery conduit leading from said tank, a return conduit leading from said tank to said reservoir, valve ports and a single valve operating member for controlling flow through said several conduits, a registering device coöordinated with said member to register a unit volume of liquid when said member is turned to permit flow through said filling conduit, and means for measuring and registering the volume of liquid that flows through said return conduit after liquid has been delivered through said delivery conduit.

9. In a liquid storage and delivery apparatus, the combination of a storage reservoir, a measuring tank, a filling conduit connecting said reservoir with said tank, a delivery conduit leading from said tank, a source of air pressure, conduits leading from said pressure source to said reservoir and tank, valve ports and a single valve-operat-

ing element for controlling first the flow of compressed air to said reservoir and the flow of liquid from said reservoir to said tank, and secondly the flow of compressed air to said tank and the flow of liquid from said tank through said delivery conduit.

10. In a liquid storage and delivery apparatus, the combination with a storage reservoir, a measuring tank, a filling conduit connecting said reservoir with said tank, and a discharge conduit; of a return measuring tank, conduits connecting said return measuring tank with said measuring tank and with said reservoir, a registering device, and float actuated mechanism in said return measuring tank for operating said registering device to register the volume of liquid returned to said reservoir after a measured volume of liquid has been removed from said measuring tank through the discharge conduit.

In testimony whereof I have hereunto set my hand.

JOHN M. MILLER.
